HENRY W. MERRITT, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 888,832.

Specification of Letters Patent.

Patented May 26, 1908.

Application filed November 29, 1904. Serial No. 234,755.

To all whom it may concern:

Be it known that I, HENRY W. MERRITT, citizen of the United States, and resident of Syracuse, in the county of Onondaga and 5 State of New York, have invented certain new and useful Improvements in Type-Writing Machines, of which the following is a specification.

This invention relates to typewriting machines and more particularly to the type bar actuating mechanism of such machines.

The main object of the invention is to improve the connection between the type bar and the means for actuating it.

15 To the above and other ends, my invention resides in the features of construction and combinations of devices hereinafter more fully set forth and particularly pointed out in the concluding claims.

20 In the accompanying drawings, Figure 1 is a skeleton view in side elevation of a type bar and its actuating mechanism. Fig. 2 is a front elevation, partly in section, of parts of a typewriting machine illustrating my invention. Fig. 3 is an enlarged fragmentary top plan view of the pivot end of a type bar and its connecting link. Fig. 4 is a view taken on the line $x-x$ of Fig. 3. Fig. 5 is a sectional view taken on the line $y-y$ of Fig. 3.

25 Fig. 6 is an enlarged fragmentary side elevation of the upper portion of one of the sub-levers. Fig. 7 is a sectional view taken on the line $z-z$ of Fig. 6.

In the drawings, the reference 1 indicates 35 the frame of the machine; 2, the platen; 3, one of a series of key levers fulcrumed at 4 and each provided with a key cap 5 and a restoring spring 6. Pivoted at 7 to each key lever is a vertically disposed sub-lever 8, the 40 lower end whereof is formed with a slot 9 which embraces a fixed fulcrum rod 10 which passes from side to side of the machine beneath the series of key levers and is secured in the base 1. The upper end of each sub-lever 8 is connected with a type bar 11 by a link 12 in a manner presently to be more fully described. Each type bar is provided with a type block 13 carrying one or more types, the forward end of said type bar normally contacting with a type rest 14 and the rear end thereof being pivotally secured to a hanger 15. The hanger 15 is one of a radially arranged series and is secured by a headed

screw 16 to a segmental vertically arranged support 17, said support being guided and 55 sustained by the side guides 18 mounted on the frame 1.

As best appears in Fig. 4, the rear upper portion of the main central part of the type bar 11 is cut away at 19 and to each side of 60 this rear portion is suitably secured a side member or cheek piece 20 (Figs. 3 and 5), preferably by rivets 21. The tail of the type bar, comprising three thicknesses or plies of metal, namely, the two side portions or cheek 65 pieces and the main central portion, is perforated to receive the pivot pin 22, which passes through the three plies of metal at right angles to the outer faces of the cheek pieces, and the ends of the pivot have their 70 bearings in the hanger 15. The cheek pieces 20 are cut out or shaped to match substantially the shape of the rear end of the central portion of the type bar, so as to produce a rigid and solid construction and one in which 75 there is a long seat or bearing for the pivot of the type bar, thus enabling the pivot to be held securely in position. Insofar as the ball-and-socket joint is concerned, the cheek pieces 20 need not be made co-extensive with 80 the entire rear end of the type bar but only long enough or of a shape or size to provide the socket portions for the ball-shaped end of the link.

Above the cut-away 19 of the main central part of the bar the inner face of each cheek piece 20 is recessed or depressed at 23 to receive the rounded, spherical or ball-shaped forward end 24 of the connecting link 12. The rear portion of the link 12 is 90 flattened at 25 and has secured in it near its end a pin 26 formed with a head 27, the under or lower portion of said head being flattened or cut away at 28.

The upper end of each sub-lever 8, as 95 appears most clearly in Figs. 6 and 7, is formed with an elongated slot larger in diameter at the lower end than at the upper and which for convenience will be called a key-hole slot 29. Secured to the sub-lever 100 below the key-hole slot in any suitable manner, as by a rectangular rivet 30, is a flat locking spring 32, the free end of which is bent inward at 33 so that it normally stands within the key-hole slot 29 and terminates at a distance 105 below the top of said slot slightly greater

- than the diameter of the pin 26. By this arrangement, under any stress tending to withdraw the pin 26 from the slot, the head 27 of said pin is caused to engage with the 5 face of the sub-lever 8 above the top of the key-hole slot, and thus the link is prevented from being accidentally separated from the sub-lever. The locking spring is formed near its free end with side lugs 34 by which 10 it may be conveniently pulled away from the sub-lever sufficiently to admit of the pin 26 being withdrawn from the larger part of the key-hole slot so as to disconnect the link 12 from the sub-lever.
- 15 In practice, each type bar and its connecting link are assembled before being secured in place on the type bar supporting segment. After the key levers and their associate sub-levers have been assembled 20 in the machine and after the type bar hanger and the type bar pivoted therein have been radially adjusted and secured, as seen in Fig. 2, the connecting link 12 of each type bar may be turned in its recesses or sockets 25 in the cheek pieces in said type bar until the flat portion 25 is vertical, whereupon the pin 26 may be passed through the enlarged portion of the key-hole slot 29 of its associate sub-lever or actuating member and lifted to 30 the upper narrow portion of said slot and over the free end of the spring, and thus locked in place by the latter, as shown in Figs. 6 and 7. The cut-away portion 28 of 35 the head of the pin enables the top of the locking spring to be arranged close enough to the top of the key-hole slot to permit a snug fit of the pin 26 to be obtained, thereby preventing looseness and rattle in the connection. By the employment of this construction, a considerable saving of time is 40 effected in assembling the parts of the type bar actuating mechanism, as it is only necessary to snap each pin 26 into place in the associate sub-lever after the parts have been 45 mounted in the machine, as above described. A further advantage is that as the sides of the bar surrounding the pivot hole are in the same planes as the remainder of the rear portion of the type bar, or in other words, 50 as the sides of the bar at the pivotal end are perfectly flat, the pivot 22 may be adjusted or fitted therein with great accuracy.
- While I have shown my invention as embodied in the Monarch typewriting machine, it is, of course, to be understood that 55 it may be applied to other forms of writing machines; and it is further to be understood that various changes in arrangement and construction of the parts may be effected 60 within the scope of the invention, and that some parts of it may be used without others.
- The ball and socket connection between the type bar and its associate connecting-link enables the latter to be revolved on its 65 longitudinal axis to any desired position.

Consequently whatever the means employed, whether that shown or some other, to connect the link with the sub-lever or actuating member, the said link in any case may, without twisting or otherwise permanently altering its original structure, be revolved until it is in the proper position to be connected with its associate actuating member, this revolution being possible because of the fact that the link is substantially straight and its longitudinal axis passes through the center of the ball carried at the end of the link.

It will be noted that the type bars swing in radial planes to and from the printing point, while the upright sub-levers vibrate in substantially vertical parallel planes. The rear end of each connecting link moves in an arc of a circle, thereby causing the pivot end of said link to move up and down. In the case of the outside type bar, as will be perceived from an inspection of Fig. 2, this up and down movement of the link causes the latter to swing nearly straight across from one cheek piece towards the other; while in the case of the center type bar the up and down movement of the link will be in a plane parallel to the planes of the inner faces of the cheek pieces. In the case of the links of the type bars intermediate the center bar and the outside bar, the movement varies between the two extremes. Furthermore, if there is any looseness or other imperfections in the sub-lever or key lever so that the upper end of said sub-lever, instead of moving in a vertical plane, vibrates in and out of said plane, the ball and socket joint permits such a lateral movement to take place without causing any bind in the joint itself. The central portion of each type bar and its cheek pieces, it will be perceived, form a trough or open top box wherein the connecting link plays freely up and down or from side to side or in an intermediate direction, thereby allowing free movement of the parts of the type action in any direction; and furthermore said link rotates freely on its longitudinal axis so that said link may be connected with its associate sub-lever without bending or twisting either link or sub-lever.

The herein shown and described construction of detachable joint between the rear end of the link and the upper end of the sub-lever is not claimed *per se* herein for the reason that it is the invention of Edwin E. Barney.

What I claim as new and desire to secure by Letters Patent, is:—

1. In a typewriting machine, the combination of a type bar having a recess and a trough-like portion, a connecting link adapted to play in said trough-like portion and having a rounded end fitting into the recess in said type bar, an actuating member connected with said link, one of said member and link elements being formed with a slot, a pin on

the other element engaging said slot, and means on the slotted element for locking said pin in place.

2. In a typewriting machine, the combination of a type bar comprising a main body portion and cheek pieces having depressions, said body portions and cheek pieces forming a trough or open-topped box, a link adapted to play in said trough and having a rounded end fitting into the depressions in the cheek pieces, a member connected with said links for actuating said type bar, one of said link and member elements being formed with a slot, a pin on the other element engaging said slot, and means on the slotted element for locking said pin in place.

3. In a typewriting machine, the combination of a three-ply type bar, the center ply being cut away to form a trough, a link adapted to play in said trough and provided with a spherical end bearing in the side plies of said type bar, and means connected with said link for actuating said type bar.

4. In a typewriting machine, the combination of a type bar comprising a body portion and side parts secured to the body portion near the pivot end and conforming with said body portion in shape, said body portion being cut away so as to form a trough or groove, and said side parts having depressions, a link adapted to play in said trough or groove and provided with a spherical end bearing in the depressions in the side parts, and means connected with said links for actuating said type bar.

5. In a front strike typewriting machine, the combination of a series of front-strike pivoted type bars, a series of keys, a series of upright levers operated by said keys, and a series of links connecting said levers with said type bars, each of said links being connected with its type bar by a ball and socket joint that permits the link to be turned about its longitudinal axis, so that it may be properly connected with its lever without twisting or bending, and each of said links being connected with its lever by a separable pin and slot connection.

6. In a typewriting machine, the combination of a three-ply type bar, the three plies being fixedly secured together and the inner faces of the outer plies having depressions therein, a connecting link having a rounded end seated in the depressions in said type bar, and means connected with said link for actuating said type bar.

7. In a front strike typewriting machine, the combination of a type bar support, a series of type bars radially mounted on said support, each type bar comprising a main central portion and recessed side portions, a series of connecting links having rounded ends seated in the recessed side portions of the type bars, a series of actuating levers detachably connected with said links, and

means for locking said links and their associate levers together.

8. In a typewriting machine, the combination of a type bar support, a series of recessed type bars radially mounted on said support, a series of connecting links each having one end rounded and seated in the recesses in one of the type bars, and each having a pin in the other end, a series of slotted levers for actuating said type bars, the slots in said levers being adapted to receive the pins on said links, and means for locking the pins in the slots.

9. In a typewriting machine, the combination of a type bar support, a series of recessed type bars radially mounted on said support, a series of connecting links each having one end rounded and seated in the recesses in one of the type bars, and each having a pin in the other end, a series of slotted levers for actuating said type bars, the slots in said levers being adapted to receive the pins on said links, and locking springs secured to said slotted levers and adapted to lock the pins of said connecting links in the slots of said slotted levers.

10. In a front strike typewriting machine, the combination of a type bar support, a series of type bars radially mounted on said support, each type bar comprising a main central portion and recessed side portions, a series of connecting links having their forward ends rounded and seated in the recessed side portions of the type bars, and having headed pins in their rear ends, a series of sub-levers having their upper ends slotted and adapted to receive the headed pins of said links, springs secured to said sub-levers and adapted to lock the headed pins of said links in the slots in said sub-levers, and key levers connected with said sub-levers.

11. In a typewriting machine, the combination of a series of front-strike type bars which swing in radial planes towards the printing point, a series of upright sub-levers, and a series of connecting links between the type bars and the sub-levers, each of said links having a detachable connection at one end with one of said sub-levers and being connected at its other end to one of said type bars by a ball and socket joint that permits the link to be turned about its longitudinal axis to an unlimited extent.

12. In a typewriting machine, the combination of a series of front-strike type bars which swing in radial planes towards the printing point, a series of upright sub-levers, and a series of connecting links between the type bars and sub-levers, said links having a flat vertical portion detachably connected with the sub-levers, said links at their opposite ends having balls which are loosely mounted in sockets in the type bars, the construction being such that the links when detached

from the sub-levers are capable of unlimited rotary movement about their own longitudinal axes on the type bars with which they are connected.

- 5 13. In a typewriting machine, the combination of a type bar, a link member having a ball and socket connection with said type bar, a lever member connected with said link member, one of said members having a slot, 10 a pin extending from the other member through said slot, and locking means on the slotted member and coöperative with said pin.
14. In a typewriting machine, the combination of a type bar, a link member having a ball and socket connection with said type bar, a lever member connected with said link member, one of said members having a slot, a headed pin extending from the other member through said slot, and a locking 20 spring on the slotted member which spring coöperates with said headed pin.
15. In a typewriting machine, the combination of a type bar, a link member having a ball and socket connection with said type bar, a lever member connected with said link member, one of said members having a slot wider at one end than at the other, a pin extending from the other member through the 25 slot and having a head provided with a flat side next to the wider end of the slot, and a 30

spring on the slotted member provided with a portion entering the slot past the flattened side of the head of said pin.

16. In a typewriting machine, the combination of a series of front-strike type bars, a series of up-standing sub-levers for actuating said type bars, and links detachably connecting said sub-levers with said type bars, said links being substantially straight and each 40 pivoted at one end to a sub-lever and having at its other end a ball seated in a socket of a type bar.

17. In a front-strike typewriting machine, the combination of a system of type bars 45 provided with sockets, upstanding sub-levers, key-actuated devices connected with said sub-levers, links each pivotally connected with one of said sub-levers at one end and at the other end being provided with a ball 50 seated in the socket of one of said type bars, the longitudinal axis of each link passing through the center of its ball and means whereby each of said links detachably connects the associate type bar and sub-lever. 55

Signed at Syracuse, in the county of Onondaga, and State of New York, this 25th day of November A. D. 1904.

HENRY W. MERRITT.
